BONE CONDUCTION TELEPHONE RECEIVER

Joachim Wolff, London, England, assignor to
Fortiphone Limited, London, England, a company of Great Britain

Application July 3, 1950, Serial No. 171,921

Claims priority, application Great Britain
July 25, 1949

5 Claims. (Cl. 179—107)

1

This invention relates to bone conduction telephone receivers that is to say to telephone receivers such as are frequently employed in deaf aid apparatus wherein sound vibrations are received by the listener by conduction along his bones rather than through the normal passages of the ear.

In bone conduction receivers it is usually necessary to provide for fine adjustment of the gap between the pole pieces of the receiver and the armature thereof. Since this gap is very small—it may be only about one half of a thousandth of an inch—considerable difficulties are experienced in providing for this adjustment. Among the numerous ways which have been proposed for providing for this adjustment are (1) employing pointed fine pitch adjustment screws to press against and thus deform the usually provided diaphragm which carries the armature (2) providing a fine threaded portion on the pole piece to enable said portion to be screwed back and forth towards or away from the armature (3) mounting the pole piece in a movable sleeve which can be tightened and thus fixed in position when the pole piece has been correctly adjusted and (4) using L-shaped pole pieces which can be deformed and thus moved in relation to the armature by fine pitch adjustment screws. All these and other proposals which have been made present more or less serious practical defects. The known arrangements depending upon fine pitch screws present the defect that since necessarily the threaded holes for the screws are a little larger than the screws themselves some play is possible and though it is small the arrangements are such that it is large enough to be the cause of appreciable back-lash in adjustment. In arrangements in which the pole piece itself is adjustable vibration of the receiver when in use tends to cause the adjustment to move and if lock-nuts are provided to prevent this, the action of locking tends to upset the previously made adjustment. In addition to these defects the arrangements in which the L-shaped pole pieces are deformed present the disadvantage that there is only one position of adjustment in which the pole pieces are parallel to the armature. In brief, the known proposals fall far short of satisfying the onerous requirements of easily made, permanent, fine adjustment which is substantially free from back-lash, requires no locking which tends to upset an adjustment already made, and is not liable to disturbance by vibration of the receiver when in use.

2

According to this invention adjustment of the pole-piece-armature gap of a bone conduction telephone receiver is effected through the medium of one or more resilient deformable members each of which bears upon the flexible support for the armature and each of which is subjected to adjustable deformation by an adjustment member.

The adjustment members are preferably 10 screws.

In the preferred embodiments the adjustment members act through resilient strip deformable members which are bent thereby and so arranged that a given movement of an adjustment member will produce a considerably smaller adjustment movement of the flexible support for the armature. Accordingly fine adjustment is rendered much easier. Locking means may be used if desired without the serious disadvantages hitherto encountered in known arrangements: where the adjustment members are screws they can be locked, after adjustment, by means of lacquer or by locking grub screws or lock nuts.

Since the resilient deformable members partly take to some extent of the nature of auxiliary diaphragms in contact with the main flexible support for the armature (which may be regarded as the main diaphragm) they affect the frequency response of the receiver. This is, from the manufacturing and design point of view, an advantage and by suitably selecting the dimensions and materials of those members the frequency response of a receiver may be made to follow closely a desirable frequency characteristic. It is, therefore, possible to produce a range of receivers of the same general design but with different frequency response characteristics to meet the requirements of different users.

By employing a plurality of symmetrically disposed strip resilient deformable members equally spaced round a flexible support for the armature—e. g. three at 120°—it is possible to ensure exact parallelism between armature and pole piece across the gap.

The invention is illustrated in the accompanying drawings. Figures 1 to 4 show one embodiment and Figure 5 shows a modification. In the drawings Figure 1 is an elevation partly in section, Figure 2 is a plan with one arm of the three-armed flexible support for the armature broken away to show one of the resilient deformable members underneath, Figure 3 is a plan of the ring magnet, and Figure 4 is a plan of the 50 back plate and coil assembly of one embodiment

while Figure 5 is an elevation partly in section, of a modification.

Referring to the drawings these show a bone conduction telephone receiver unit comprising three main sub-assemblies namely a back plate 5 core and coil assembly A, a ring magnet B, and a front plate, armature and adjustment assembly C.

The sub-assembly A comprises a ferro-magnet back plate A1 with an upstanding central pole piece A2 on which is a coil A3 and which has a ring of six holes of which three alternate holes A4 are large and the other three A5 are small. The two additional small holes A6 pass the leads to the coil A3.

The ring-magnet sub-assembly consists of one part, namely the ring magnet B itself, which is formed with a ring of six half-holes B1 in line with the holes A4 and A5 when the sub-assemblies are put together.

The sub-assembly C, with which this invention is concerned consists of a top plate C1 on which is carried, by means of screws C2 screwing thereon, a flexible support or diaphragm member for the armature. This support is in the form of a three armed spider C3 the outer ends of the arms of which are drilled to pass the shanks of the screws C2. Each screw C2 passes first through a hole in the appropriate spider arm, then through a spacing collar C4, then through a hole in the end of a deformable adjustment member C5. The centre of the spider has a central hole and the armature structure, which is not shown in detail since it forms per se no part of this invention is carried from the centre of the spider by means of its two parts C6, C7 which screw together to clamp the centre of the spider between them. Deformable adjustment strips which are of springy, deformable metal, lie underneath the arcuate outer parts of the spider arms and each has an upturned end C8 which bears against the underside of the appropriate arcuate outer part about half way between its anchoring screw C2 and the radial part of the arm. Adjustment screws C9 screw into tapped holes in the top plate C1 and each, when screwed up, presses up from underneath against the appropriate adjustment strip C5 about a third of the way along from its anchored end.

The three sub-assemblies are put together in line as shown in Figure 1 with the magnet B between the sub-assemblies A and C. The large holes A4 are big enough to pass the heads of the adjustment screws C9 which lie in said holes and are accessible for adjustment. The small holes A5 which are countersunk on the under side pass the shanks of screws C10 which screw into tapped holes in the top plate C1 and hold the sub-assemblies together with the lower face of the armature spaced by a small (adjustable) air gap from the top face of the central pole piece A2 and the top face of the top plate C1 which is coplanar with the said pole piece face.

As will be apparent, with this arrangement adjustment of the screws C9 varies the pressure with which the ends of the adjustment members C5 bear against the spider arms and therefore varies the armature-pole piece gap. Further, since the members C5 are resiliently deformable they bend under the pressure of the screws C9 so that a relatively large longitudinal movement of one of these screws produces a considerably smaller movement of the spider arm affected. Accordingly close adjustment is facilitated and the hereinbefore described defects of known

arrangements are avoided or greatly reduced. The screws C9 may be locked by painting them with lacquer or any other convenient locking means may be used if required. As will be obvious to those skilled in the art other means known per se may be used instead of the illustrated screws C9 for adjusting the member C5 e. g. adjustment wedges, rollers, cams or bars.

A telephone unit as above described and illustrated is mounted in a suitable casing (not shown)—for example of the material known under the registered trade mark of "Bakelite"—such mounting being most conveniently fitted by drilling and tapping the centre of the upper or 10 clamping part of the armature structure, and employing a bolt which passes through the centre of the back of the casing into this drilled and tapped hole and therefore holds the armature firmly up against the inside of the back of the casing. This holding bolt is thus the sole support for the telephone proper. In use pressure sound waves are transmitted to the back of the casing and then through the casing to the front thereof, which is made of suitable hollow shape 15 as known per se to fit comfortably and efficiently against the sound receiving bone of the wearer.

In the modification shown in Figure 5 each of the deformable strip shaped adjustment members C5 of Figure 1 is replaced by a coiled spring C55 which may be helical or, as shown spiro-helical. The compression of this spring is adjusted by an adjustment screw C59 and the upper end of the spring i. e. the end remote from the screw C59 has inserted therein the stem part 20 of a taper headed member C58 which performs a function similar to that of the parts C8 of Figure 1 and bears against the underside of the appropriate arm of the spider C3, where, if desired, a small "dimple" may be formed to receive the 25 point of the head of the member C58. It is thought that the remainder of Figure 5 will be self-evident from the description already given of Figure 1, like parts in both figures carrying the same references.

I claim:

1. In a bone conduction telephone receiver unit having an armature supported adjacent a magnetic pole piece by flexible support means providing an air gap between said armature and said pole piece, adjustment means for adjusting said air gap, said adjustment means comprising a resilient deformable member engaging said flexible support means and constituted by an anchored strip and means engaging said deformable strip member intermediate the anchorage of said strip member and where said strip member engages the flexible support means, adjustably to deform the same.

2. A unit as claimed in claim 1 wherein said flexible support means is a flexible spider having arms one of which is engaged by the resilient deformable member.

3. A unit as claimed in claim 1 wherein said flexible support means is a flexible spider having arms each having a radial portion extending into an arcuate portion anchored at the far end and one of which is engaged by the resilient deformable member between the ends of said arcuate portion.

4. In a bone conduction telephone receiver unit having an armature supported adjacent a magnetic pole piece by flexible support means providing an air gap between said armature and said pole piece, adjustment means for adjusting 70 said air gap, said adjustment means comprising

a resilient deformable member engaging said flexible support means and means engaging said deformable member adjustably to deform the same, said flexible support means being a flexible spider having a plurality of arms and said resilient deformable member being a strip anchored at one end and having its other end upturned to engage an arm of said spider.

5. In a bone conduction telephone receiver unit having an armature supported adjacent a magnetic pole piece by flexible support means providing an air gap between said armature and said pole piece, adjustment means for adjusting said air gap said adjustment means comprising a resilient deformable member engaging said flexible support means and constituted by an anchored strip and a screw engaging said deformable strip member intermediate the anchorage of said strip member and where said strip member engages the flexible support means, adjustably to deform the same.
